UNITED STATES PATENT OFFICE.

FREDERIC F. BAHNSON, OF WINSTON-SALEM, NORTH CAROLINA.

HUMIDIFIER.

Application filed June 30, 1924. Serial No. 723,404.

This invention relates to humidifiers of the type which distributes moisture directly into the air of the room or other space in which a controlled humidity is desired, and more particularly to small and portable humidifiers adapted for use in residences.

An object of the invention is to provide a small humidifier which will deliver a maximum quantity of moisture to the air. An object is to provide a simple and inexpensive humidifier which is comparable in operation to portable electric fans and heaters. More specifically an object of the invention is to provide a humidifier in which all of the working parts are carried by a supporting frame which may be placed upon or over a receptacle for holding water.

These and other objects of the invention are attained in the embodiment of my invention which is illustrated in the accompanying drawing, in which the single figure is a vertical section taken through the humidifier.

In the drawing, the numeral 1 designates a receptacle for holding water, which receptacle is preferably provided with a peripheral flange and shoulder 2 upon which the frame and operating parts of the humidifier may rest. As shown, the frame comprises three straps or legs 3 forming a tripod support for a motor 4, which is arranged with the armature shaft 5 in vertical position. The moving parts, which are all mounted upon the shaft 5, are a fan 6, a water distributing disk 7 and a water elevator 8. The water elevator 8 is constructed as a tube of uniform diameter having a bushing 9 at its upper end by means of which the tube is connected to the motor shaft. The tube 8 is of such length as to depend well below the frame 3 and is provided with a lower end wall 10 having an opening therein of less diameter than the inside diameter of the tube 8. The end wall 10 is preferably formed as an inverted truncated cone and may, if desired, be provided with a shallow cross blade 11 to assist in the lifting operation. Above the upwardly flaring disk 7, the tube 8 is provided with one or more apertures or rows of apertures through which water which travels up the inner face of the tube may be delivered to the disk 7. Adjacent the periphery of the disk 7 is an annular set of stationary blades 12 which break up the water thrown from the disk.

A portion of the air current delivered by the fan 6 passes outwardly over the upper face of the disk and another portion passes through openings 13 in the disk, and then outwardly between the lower face of the disk and the water, the disk being preferably provided with blades 14 which assist in establishing the lower air current. Obviously the openings 13 lie inside of the points at which water thrown from the water elevator strikes the disk.

The operating parts are enclosed by members which direct the moist air from the humidifier in a horizontal direction and which also serve to return to the water supply any drops of water which settle out of the air current. The lower portion of the casing comprises a shell 15 whose lower edge preferably engages the flange 2 of the water receptacle with a sliding fit. The upper edge of the shell is turned inwardly, forming a flange 16, and an upwardly and outwardly flaring member 17 is mounted upon the frame 3 and spaced from the flange 16. The lower portion of the member 17 carries a horizontal plate 18 which extends towards the shell 15 and lies below the outlet opening, thus constraining the moist air to follow a tortuous path. It will be noted that the surfaces along which the moist air travels will return any precipitated moisture to the receptacle.

The humidifier casing is preferably completed by a shell 19 which rises from the member 17 and extends above the motor 4. The air enters through the open end of the shell 19, which open end is preferably provided with a guard such as a wire screen 20. The inner end of the casing 17-19 is closed, except for the central outlet directly above the fan 6.

In some cases the speed of rotation of the water elevator and the shape of the water receptacle may be such that the entire body of water tends to travel about the receptacle. To prevent this action, crossed ribs 21 may be provided below the elevator tube.

The humidifier will, of course, be controlled by a humidistat of any suitable type, which humidistat will be located at some point remote from the moist air outlet of the humidifier. The choice and location of the humidistat, however, form no part of the present invention.

When current is supplied to the motor, an air current is established which moves

downwardly upon the rotating disk 7, part of the air then moving laterally along the upper face of the disk, while the other portion passes through the disk and then moves outwardly between the disk and the surface of the water. The rotation of the elevator tube 8 lifts water from the receptacle and discharges it upon the upper face of the disk, the path taken by the water being indicated by the arrows. Due to formation of the elevator tube 8 as a right circular cylinder, water is prevented from traveling up the outside of the tube, the entire flow taking place along the inner wall. The water is thrown from the disk with a high velocity and is atomized by impact against the blades 12. Due to the provision of an air current below the level at which the water is atomized, the evaporating capacity of the humidifier is very high as only the larger drops or particles of water can sink through this air current. Some relatively large particles will be taken up by the air currents, but such particles will be deposited upon the surfaces which define the tortuous outlet passage and will flow back into the receptacle.

It will be apparent that the embodiment described herein is illustrative of my invention, and that many changes may be made in the various parts, their relative size, shape and location without departing from the invention as set forth in the following claims.

35 I claim:

1. In a humidifier, a supporting frame, a motor carried by the frame, a tube depending from said frame and having an opening near the upper end thereof, said tube being rotatable by said motor to deliver water through said opening, a fan located above said opening and establishing a current of air downwardly along said tube, and means carried by and extending laterally from said tube below said opening to receive water delivered therethrough, said means having openings therethrough permitting a portion of said air current to cross the path taken by the water and to move outwardly from said tube below the said laterally extending means.

2. In a humidifier, a supporting frame adapted to be supported by the walls of a water-holding receptacle, a motor carried by said frame, a water elevator operated by and depending below said motor, said elevator having an opening near the upper end thereof, fan blades carried by said elevator between said opening and said motor for establishing a current of air downwardly along said elevator, a water-throwing disk below said opening for receiving water delivered therefrom, and means adjacent the

periphery of said disk for breaking up the water thrown from said disk.

3. In a humidifier, a cylindrical tube adapted to be rotated by a motor, an opening near the upper end of said tube, a lower end wall for said tube comprising a truncated cone tapering downwardly from the side wall of the tube, a fan carried at the upper end of said tube, and a water-receiving and delivering disk carried by said tube below said opening.

4. The invention as claimed in claim 3, wherein said disk is provided with apertures near said tube to permit the passage through said disk of air delivered by said fan.

5. In a humidifier, a frame adapted to be positioned above a water-holding receptacle, a motor on said frame and having a vertically arranged shaft, a tubular water elevator carried by said shaft, a fan at the upper end of and adapted to deliver a current of air axially of said water elevator and an upwardly flaring disk on said tubular elevator below said fan and having its central portion located below the water delivery outlet of said elevator, said disk being provided with apertures adjacent the axis thereof.

6. In a humidifier, a frame adapted to be positioned above a water-holding receptacle, a motor on said frame and having a vertically arranged shaft, a tubular water elevator carried by said shaft, a fan at the upper end of and adapted to deliver a current of air axially of said water elevator, and a disk on said water elevator below said fan, said disk comprising a flat apertured portion positioned below the water delivery outlets of said elevator and an outer portion flaring upwardly and outwardly from said flat apertured portion to receive and distribute water thrown centrifugally from the outlets of said water elevator.

7. The invention as set forth in claim 6, wherein said flat portion of said disk is provided with blades for assisting the passage of air downwardly through the apertures in said flat portion of the disk.

8. A humidifier comprising a receptacle for holding water, a supporting frame, a motor thereon, a fan below said motor, a water-elevating tube operated by said motor and depending below said fan, said tube having an opening near the upper end thereof, a disk carried by said tube and below said opening, means for atomizing water thrown from said disk, and passages through the central portion of said disk for permitting a portion of the air delivered by said fan to pass through said disk and outwardly along the lower face thereof.

In testimony whereof, I affix my signature.
FREDERIC F. BAHNSEN.
